DESIGN FOR A VANITY HANDBAG

Irwin M. Robbins, Rockville Centre, N. Y.

Application January 28, 1938, Serial No. 74,620

Term of patent 3½ years

To all whom it may concern:

Be it known that I, Irwin M. Robbins, a citizen of the United States, and resident of Rockville Centre, Long Island, in the county of Nassau and State of New York, have invented a new, original, and ornamental Design for Vanity Handbags, of which the following is a specification, reference being had to the accompanying drawing, forming a part thereof, and of which Figure 1 is an isometric perspective view in closed position, and Fig. 2 is an isometric perspective view with both compartments open, of a vanity handbag showing my new design.

The rear side of the vanity handbag is substantially plain.

I claim:

The ornamental design for a vanity handbag substantially as shown and described.

IRWIN M. ROBBINS.
